UNITED STATES PATENT OFFICE.

CHARLES C. CREWSON, OF KANSAS CITY, MISSOURI; BESSIE ALLEN ADMINISTRATRIX
OF SAID CHARLES C. CREWSON, DECEASED.

DOOR-ANCHOR MECHANISM.

Application filed December 7, 1925. Serial No. 73,821.

My invention relates to improvements in door anchors and has special reference to a door anchor adapted to hold a door at a predetermined point.

5 The door anchor of my invention belongs to the brace-bar rather than the plunger class and has for its object to produce an improved door anchor of the class referred to which is positive and efficient in action, 10 easily manipulated by the foot or hand of the operator, and simple means for holding and locking the brace-bar when in inoperative position.

A further feature of my invention relates 15 to a triangular hole in the brace-bar pivotally receiving a pivot pin adapted to engage the brace-bar in its various functions, and the free end of the brace-bar tapered and encased by a rubber thimble adapted to form 20 a vacuum for cushioning the brace-bar when in contact with the floor to prevent slipping or marring fine fabric floor coverings.

With these objects in view the invention 25 consists in certain novel and useful features of construction and combination of parts as hereinafter described and claimed, and in order that it may be fully understood, reference is to be had to the accompanying drawings in which:—

30 Fig. 1 is an elevational side view of the device shown in inoperative position on the door.

Fig. 2 is a longitudinal sectional side view 35 of the device shown in operative position on the door and in contact with the floor.

Fig. 3 is a fragmentary side view of the device at its pivoted end showing the triangular hole in the brace-bar and its achievements.

40 Fig. 4 is a perspective view of a door showing the invention attached thereto.

Fig. 5 is a side view of the device bracket.

Fig. 6 is an end view of the device bracket.

Fig. 7 is a horizontal sectional view taken 45 on the line A—B of Fig. 2.

Referring now to the drawings in detail, 1 indicates a vertical swinging door upon which the device is adapted for installation. The device comprises a metallic bracket 2 50 consisting of a base plate 3 perforated for receiving fastening screws or bolts; two upturned lugs 4 adapted to receive one end of a swinging metallic brace-bar 5 a tapered shoulder 6 rigid with the lugs 4 for engaging 65 the end of the brace-bar 5 and rigidly

locking it when swung to inoperative position. A boss or stop 7 depends from the base plate 3 of the bracket adjacent the lugs 4 to prevent the brace-bar 5 contacting with the door 1 and to align the brace-bar 5 60 for engaging with the tapered shoulder 6 when swung into inoperative position. Pivotally mounted between the lugs 4 by the pivot pin 8 is the brace-bar 5 provided at one end with a triangular hole 9 pivotally receiving the pivot pin 8 and the opposite end mounted with a rubber thimble 10 for the purpose of obtaining contact with the floor and prevent slipping or marring fabric floor 65 coverings when in operative position. The triangular hole 9 performs several functions. First, when the brace-bar is swung to inoperative position causes it by gravitation to drop down and engage the tapered shoulder 6 and hold and rigidly lock it in a 70 vertical and inoperative position; second when the brace-bar is swung to operative position, and should there be any protuberance in the floor, it will cause adjustment and impinge squarely against the floor; 75 third, when the brace bar is being swung in its various positions, the bearing lines against the pivot pin permits and causes the brace-bar to rotate around the pivot pin with perfect accuracy without binding against 80 the bracket lines, and causes it to automatically seat itself in operative and inoperative 85 positions.

To prevent the brace-bar 5 being forced beyond its straining line as shown in dotted line C—D Fig. 2, and becoming locked in operative position and the backward movement of the door to its limit, I provide the hook-shaped lug 11 to contact with the bracket base 3 and limit its movement in 90 this direction. Also the hook-shaped lug 11 provides means for manipulating the brace-bar by the toe of the shoe of the operator in its various operations. At the free and tapered end of the brace-bar 5 encased in 95 the rubber thimble 10 I provide a vacuum space 12 adapted to form an air cushion for resilient action when in contact with the floor, and obviate the marring of fine fabric floor coverings.

100 From the above description it will thus be apparent that I have produced a door anchor mechanism embodying the features of advantage enumerated as desirable in the statement of the objects of the invention,

and while I have illustrated and described the preferred form of embodiment of the invention, it will be apparent that it is susceptible of modification in minor particulars 5 without departing from the principle of construction or mode of operation involved.

What I claim is:

1. A door anchor mechanism comprising a bracket adapted to be secured to the door, 10 a brace-bar, means for pivotally mounting the brace-bar at one end for swinging movement, said brace-bar at its pivotal connection having a triangular hole for engaging the pivot pin to rotate thereon and obviate 15 binding or sliding effect on its rotating lines, and to automatically seat the brace-bar in operative or inoperative position.
2. In a device of the kind described, a bracket having a pair of outwardly-projecting lugs, a brace-bar, means for pivotally mounting the brace-bar for swinging movement, said brace-bar having a triangu-

lar hole at its pivotal end for rotating thereon, a tapered shoulder rigid with the lugs of said bracket for engaging the brace-bar 25 and holding and latching it in inoperative position, a boss adjacent said lugs to prevent the free end of said brace-bar contacting with and marring the door, and to align the said brace-bar in engagement with said 30 tapered shoulder when swung to inoperative position, the free end of said brace-bar being tapered and encased with a rubber thimble forming an air cushion to prevent slipping or marring floor coverings when 35 in contact with the floor, a hook shaped lug integral with the brace-bar for its manipulation by the toe of the shoe and to avert extreme backward movement when in operative position.

In witness whereof, I have hereunto affixed my signature.

CHARLES C. CREWSON.
